UNITED STATES PATENT OFFICE.

WILLIAM A. FRIES, OF PHILADELPHIA, PENNSYLVANIA.

STEAM-PACKING.

SPECIFICATION forming part of Letters Patent No. 269,517, dated December 26, 1882.

Application filed August 17, 1882. (No model.)

To all whom it may concern:

Be it known that I, WILLIAM A. FRIES, of Philadelphia, in the county of Philadelphia and State of Pennsylvania, have invented a new and valuable Improvement in Steam-Pack-
5 ing; and I do hereby declare that the follow-
ing is a full, clear, and exact description of
the construction and operation of the same,
reference being had to the annexed draw-
10 ings, making a part of this specification, and
to the letters and figures of reference marked
thereon.

Figure 1 is a broken elevation of a packing-
core constructed in accordance with my inven-
15 tion, and Fig. 2 is a plan of the same.

My invention has relation to flexible pack-
ing or cores for stuffing-boxes of engine-cylin-
ders and other devices; and it has for its ob-
ject to provide a core or packing which main-
20 tains itself in close impingement against the
piston-rod and the walls or sides of the stuff-
ing-box, which possesses great durability,
which resists in a marked degree the action of
heat, fire, or live steam, and which is readily
25 and cheaply manufactured.

Flexible packing, as heretofore and at pres-
ent made, is so constructed and composed of
such ingredients that the packing, when in use,
soon becomes soft and dead, settles or falls
30 away from the piston-rod and the sides of the
stuffing-box, and permits the steam to escape
therethrough, thereby necessitating frequent
adjustment of the lid of the stuffing-box to
take up the slack in the packing-core, and the
35 latter is soon worn away and becomes unfit
for use. My invention avoids such disadvan-
tages by so constructing the packing or core
that it possesses great inherent elasticity; or,
in other words, I make a springy or approxi-
40 mately springy core without in any manner
destroying the flexibility of the same.

My invention accordingly consists of a pack-
ing composed of cork, asbestos, and dissolved
45 gum, and is made of any suitable or desired
shape in cross-section. The cork gives to the
packing or core a certain amount of elasticity
or resiliency, which prevents the same from
becoming dead. The asbestos resists the de-
teriorating action of heat or fire or live steam

and preserves the core in a firm condition, so 50
that it will not soften, while the gum unites
the particles of cork and of asbestos together
to form a compact mass.

The mode of manufacturing the packing or
core is substantially as follows: I first take gran- 55
ulated cork, or cork in the form of thin shav-
ings, asbestos fiber, and dissolved gum, and
mix them well together until the cork and as-
bestus particles adhere to each other after they
have been kneaded or worked until a consist- 60
ent mass is formed. Such product is then placed
in a receptacle of any desired or convenient
size, having a round, square, or other config-
ured spout or tube projecting from its bottom,
or from its side near the bottom. When the re- 65
ceptacle is filled the material is forced out there-
of through said spout or tube by means of a
piston fitting into such vessel and operated by
a common lever, cord, rack, or any other desired
or suitable mechanism. Such material comes 70
out of the spout or tube in a continuous round
or square piece or strip, depending upon the out-
line of said spout or tube. The core so formed
is dried, and may be covered with a layer of
muslin, linen, or duck, as shown at *c*, Fig. 1, *B* 75
representing the cork granulations and *A* the
asbestos fiber; or said packing or core may have
a braided covering of hemp, asbestos, or other
material. Any desired or suitable gum may be
used, and the proportions of the ingredients 80
of the packing may be varied as desired or
as will be suggested to a skilled and expert
workman.

Such packing is not only easily and cheaply
made, but is also extremely durable, as the 85
asbestos prevents the hot steam, fire, or heat
acting thereon to soften or destroy it, while
the cork renders the same springy or elastic,
so that it is always in due condition to bear
hard against the piston-rod and the sides of 90
the stuffing or other box in which it may be
placed to form a tight joint therewith. At the
same time the packing or core possesses the
element of flexibility to the same or substan-
tially the same degree as that of ordinary pack- 95
ing.

What I claim as my invention is—

1. A packing or core composed of granulated

strips or shavings of cork, asbestos, and dissolved gum, substantially as shown and described.

2. A packing or core composed of granulated strips or shavings of cork, asbestos, and dissolved gum covered with a layer of asbestos, linen, or other suitable material, substantially as shown and described.

In testimony that I claim the above I have hereunto subscribed my name in the presence of two witnesses.

WILLIAM A. FRIES.
